Francis H. Treat,

UNITED STATES PATENT OFFICE.

FRANCIS H. TREAT, OF JOLIET, ILLINOIS.

MACHINE FOR MAKING BARBED FENCE-WIRE.

SPECIFICATION forming part of Letters Patent No. 276,505, dated April 24, 1883.

Application filed April 28, 1882. (No model.)

To all whom it may concern:

Be it known that I, FRANCIS H. TREAT, a citizen of the United States, residing at Joliet, in the county of Will and State of Illinois, have invented new and useful improvements in machines for making barbed fence-wire from wire previously provided with a lateral rib or ribs or leaves; and I do hereby declare the following to be a full, clear, and exact description of the invention, such as will enable others skilled in the art to which it appertains to make and use the same.

My invention relates to the manufacture of that kind of barbed fence-wire which consists of a stem and barbs integral therewith, the bars being formed by shearing and bending a rib or ribs or leaves on such wire.

The object of my invention is to form the barbs by a shearing and bending machine, designed more especially to operate on the leafed wire produced by the practice of the invention described in another application for United States Letters Patent filed of even date with the application for this patent, though it may be readily adapted to operate on other forms of previously prepared wire.

The invention consists of certain mechanical combinations stated in the claims at the close of this specification, and composed mainly of shearing and bending and feeding devices.

In order that my invention may be clearly understood, I have illustrated in the annexed drawings, and will proceed to describe, the best form thereof at present known to me.

Figure 1 is an end elevation of the machine. Fig. 2 is a plan view thereof. Fig. 3 is a vertical transverse section in planes indicated by lines 1 2 and 3 4 of Fig. 2. Fig. 4 is a longitudinal section (on an enlarged scale) in the plane indicated by lines 5 6 in Figs. 2 and 3. Figs. 5, 6, 7, and 8 are detailed views, (on an enlarged scale,) Fig. 7 being a vertical longitudinal section in the plane indicated by lines 7 8 in Figs. 6 and 8, and Fig. 8 being a section in the plane indicated by the lines 9 10 in Figs. 6 and 7.

The same letters of reference indicate similar parts in all the figures.

The operative parts of the machine are mounted and supported on a suitable stand or frame, A, provided at one end with bearings aa' ,

in which the main shaft B rests and turns. The main shaft carries the fast and loose pulleys B' and B'', on either one or the other of which a belt from a line-shaft is caused to run, according as the machine is to be driven or remain at rest. An eccentric, b, on the main shaft reciprocates horizontally a slide or cross-head, C, by means of the eccentric-rod b', the cross-head sliding in suitable guides, c c, on the main frame. One blade, D, of the shears is adjustably fixed upon the outer end of cross-head C, projecting some distance from the end thereof, and is moved thereby in a horizontal plane, its lower face moving just above the upper face of the other blade, E, of the shears. The blade E is adjustably fixed upon a bracket, a'', on the main frame. The cutting-edge of this blade D stands a little obliquely, so that it will cut with a shearing action, while the cutting-edge of blade E is about square, so that it may lie close along the side of the leaf to be sheared and bent. Along the side at which the leaf of the wire enters between the shears the blade E is provided with a longitudinal rib, e, of about the height of the leaf of the wire, against the side and at the base of which leaf the semicircular or rounded end of the rib is to bear when the wire is in position to have one of its leaves sheared in part from the stem. Opposite to the end of this rib e the edge of blade D is cut away to form a plunger at that point, having a substantially vertical face of ogee contour in horizontal cross-section, as shown at d. This plunger of the blade D acts, in conjunction with the rib e of blade E, to bend the sheared leaf tangentially at about right angles from the wire, as shown in Figs. 2 and 6.

The leafed wire to be operated on is fed to the combined shears and benders through a channel, x, formed in the guide-plates F F, which are secured in a seat on the main frame A and extend close up to the side of the shears and benders. The wire is introduced endwise in such manner that its round stem will occupy the rounded bottom of the channel, while its leaves project upwardly into the vertical flat portion of the channel. Thus the leafed wire will be fed with its leaves projecting upward. The channel is so aligned with reference to the shearing-edges of the shear-blades

that the latter will cut the upwardly-projecting leaves of the wire close to the round stem thereof. At the end adjacent to the shears the upper side of the vertical flat portion of the channel x terminates in a wider groove, x' , open on top. The length of this groove x' is somewhat greater than the distance from one end of a leaf on the wire to the similar end of the next adjacent leaf. The leafed wire is fed 10 intermittently to the combined shears and benders by a reciprocating pawl, G, the free end of which, being guided in the groove x' , is provided with a bit, g, adapted to enter the flat vertical portion of the channel x and successively engage the wire behind the leaves thereof, as shown in Figs. 5 and 7. The pawl is pivoted on a horizontally-adjustable pin of the horizontally-sliding yoke H, mounted on a guide-rail, a^3 , on the main frame. The pawl is 20 held to its work by a spring, g' , supported by the stud g^2 , and strained by a stud, g^3 , both of which studs are secured to yoke H. The yoke is reciprocated by the crank-pin i of the crank-disk I^2 , which crank-pin, preferably carrying 25 a roller or sleeve, as shown in Figs. 2 and 8, plays in a vertical groove, h , on the back of the yoke. The crank-disk is keyed on one end of the horizontal crank-shaft I, driven by the main shaft through the bevel-gearing I' . The throw of the crank-disk $I^2 i$ is proportioned to 30 the distance between the leaves from center to center, so that the pawl may properly feed the wire at each forward stroke, and its rotation is also properly timed with respect to the eccentric b of the main shaft, so that the wire 35 will be fed as soon as the blade D has sufficiently receded from the blade E to permit of the recently-formed barb passing by its end. In order that the wire may be firmly held 40 during the shearing and bending operations on its leaves, I provide a presser-block, K, for forcibly pressing the wire against the end of blade E. This presser-block is carried on the upright arm, k , of a lever, K', fulcrumed at k' 45 on the main frame, and reaching with its other arm to a cam, b^2 , on the main shaft B, so that said cam may operate on an anti-friction roller carried by said lever to rock the lever in opposition to a spring, k^2 , and force the presser-block against the wire. Cam b^2 is properly 50 timed with respect to eccentric b . As the grade of the cam escapes from the anti-friction roller of the lever, spring k^2 rocks the lever in the opposite direction, so as to move the presser-block away from the wire.

If it be desired to crimp the wire on this machine after the barbs have been formed, a fixed crimping-die, L, may be mounted on the bracket a and a movable crimping-die, L', on the cross-head C, as shown in Fig. 2.

As the barbed wire leaves the machine it may be wound on a gravitating reel, M, operated by the machine in the manner shown—namely, by means of a chain, m, which passes around the same core of the reel on which the wire is to be wound, so that the speed of rotation of the reel will change automatically to maintain a uniform winding surface speed. The chain m is driven by the chain-wheel N' on the counter-shaft N of the machine, driven 70 by belt-gearing from the crank-shaft I, as best shown in Fig. 1. The driving side of the chain passes directly from the reel to the chain-wheel N', while the slack side passes around the guide-pulleys m^1 , m^2 , and m^3 , of which the one marked m^2 is hung in a stirrup at the end of a rope which reeves over a fixed elevated pulley, m^4 , and carries at its other end a counter-weight, m^5 , applied to counterbalance the reel.

After the barbs have been formed on this machine the wire is to be twisted so that the barbs will stand out on all sides. The machine for performing this operation will be the subject-matter of an application for a patent which I intend to file hereafter.

Having thus described my invention, what I claim as new is—

1. The combination, substantially as before set forth, of the two combined shear-blades and benders for forming a barb on a ribbed or leafed wire by shearing and bending.

2. The combination, substantially as before set forth, of the two combined shear-blades and benders and the presser-block.

3. The combination, substantially as before set forth, of the two combined shear-blades and benders, the presser-block, the lever carrying said presser-block, and the cam for operating on the lever.

4. The combination, substantially as before set forth, of the two combined shear-blades and benders, the channel for guiding the wire, and the reciprocating pawl for feeding the wire.

In testimony whereof I affix my signature in presence of two witnesses.

FRANCIS H. TREAT.
